CLAIM

The ornamental design for a utensil caddy, as shown and described.

DESCRIPTION

FIG. 1 is a prospective view of the utensil caddy;

FIG. 2 is another prospective thereof;

FIG. 3 is a front view thereof;

FIG. 4 is a side view thereof; and

FIG. 5 is a top side view thereof; and,

FIG. 6 is another side view thereof.

The broken line showing of a container is for illustrative purposes only and does not form part of the claimed design.
